UNITED STATES PATENT OFFICE.

JOSEPH DANIELS AND WILLIAM I. SILVIS, OF CANTON, OHIO.

ROLL-POLISHER.

1,122,369.

Specification of Letters Patent. Patented Dec. 29, 1914.

Application filed July 13, 1914. Serial No. 850,587.

To all whom it may concern:

Be it known that we, JOSEPH DANIELS and WILLIAM I. SILVIS, citizens of the United States, both residing at Canton, in the county of Stark and State of Ohio, have invented a new and useful Roll-Polisher, of which the following is a specification.

Our invention relates to improvements in roll polishers for polishing the rolls of rolling mills and the like and has more particular reference to roll polishers of the character referred to which are adapted to be connected to the mill and operate continuously upon the rolls of the mill to constantly maintain the surface of the rolls in the proper condition and free from scale and the like.

The object of this invention is to provide a roll polisher of the character mentioned which will be simple and inexpensive and which may be easily attached to a rolling mill of the ordinary construction without requiring any changes in the mill.

A further object of this invention is to provide a roll polisher which will operate continuously and automatically and which may be adjusted with relation to the rolls so as to polish the rolls uniformly while they are in operation, obviating the necessity of discontinuing rolling in order to polish the rolls as has been done in the past.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made, provided they fall within the scope of the appended claims, without departing from the spirit or sacrificing any of the advantages of the invention.

In the drawings: Figure 1 is a sectional view of a rolling mill showing our roll polishers applied thereto. Fig. 2 is an enlarged transverse section through the roll polisher. Fig. 3 is a detached perspective view of the roll polisher. Fig. 4 is a plan view of the same. Fig. 5 is a fragmentary sectional view showing means at one end of the device for retaining the polishing blocks. Fig. 6 is a rear elevation of one of the blocks.

Similar numerals of reference indicate corresponding parts throughout the several figures of the drawings.

It has been the custom heretofore in the operation of rolling mills such as sheet, tin and plate mills and the like to periodically shut down the mills for the purpose of 60 polishing the rolls to remove scales and abrasions from the surface of the rolls. It is generally understood by those skilled in the art that the rolls are very expensive and difficult to make and they must be handled with a great amount of care in order to produce the proper gage and 65 quality of product when they are in operation. In order to turn out a product of the best quality the rolls must be operated as continuously as possible so that the temperature may remain substantially uniform, as when the rolls are cool the product is of inferior grade and uncertain gage. 70 While in practical use the finely polished surfaces of the rolls become roughened, scratched and abraded and what is known as scales frequently form upon the surfaces thereof. As it is necessary that the product have a smooth and even surface the 75 rolls must be maintained in proper condition to produce such a product and in the past it has been customary to frequently polish the rolls in order to maintain them in the proper condition. The common way 80 of polishing the rolls has been to discontinue rolling the product at frequent intervals and to manually polish the rolls by holding a block of carborundum or similar material against the rolls or by the use of a 85 rotary grinding wheel which is adapted to be temporarily clamped to the mill and brought into contact with the rolls. In order to polish the rolls with either of these methods it is necessary to remove a part of 90 the attachments belonging to the mill in order that the rolls may be made accessible for the polishing operation and as this 95 operation together with the polishing and subsequent assembling of the attachments 100 requires considerable time the rolls are allowed to cool and much time is lost. The product of the mill immediately after the 105 rolls has been polished will be of an inferior quality, owing to the fact that the rolls are not sufficiently heated and by the time they have been heated to the proper temperature the surfaces have again become more or less scratched and uneven so that at the time when the rolls are in the best 110 condition as to temperature their surfaces have already lost their high polish. Thus,

under these conditions, the mill is at no time capable of turning out a uniform product of the highest quality.

It is the purpose of our invention to remedy this unsatisfactory condition by providing a polishing device to be attached upon the mill and to be constantly in operation, thus maintaining the surfaces of the rolls at all times in a uniformly perfect condition and doing away with the necessity of frequently discontinuing rolling for the purpose of polishing the rolls. The rolls are thus maintained at a uniform temperature, due to their constant use, and the product formed therein will be of a uniform quality and gage and the mill may be operated continuously.

In the construction illustrated in the accompanying drawings the housing of a rolling mill of ordinary construction is indicated by the numeral 1. The upper and lower rolls 2 and 3 respectively are of the usual construction and are mounted within the housing in any common and well known manner.

Our invention comprises primarily a polishing block of carborundum, sand stone, emery, polished steel or other suitable material for the purpose intended, held in constant frictional contact with the surface of the roll, means being provided for properly distributing and varying such contact as may be required. This polishing block is preferably made up of a plurality of sections 4 of the form shown in the drawings and held together by means to be hereinafter described. Each of the sections 4 of the polishing block is provided upon its inner face with the two scraping edges 5 adapted to be held in contact with the roll. For the purpose of avoiding creases or irregularities being formed upon the roll at the point where the sections 4 are joined together, these joints are staggered, this result being accomplished by forming a V-shaped notch 6 in one end of each section and beveled faces 7 upon the opposite end of the section adapted to be received in the V-shaped notch of the next adjacent section. These blocks 8 are held firmly together and carried within a metallic frame 8 provided with end plates 9. The sections of polishing blocks rest upon the lower wall 10 of the frame and are held firmly together by means of retaining blocks 11 and 12 formed of steel, iron or other suitable material. The retaining block 11 is provided with a V-shaped notch 13 and the retaining block 12 with a beveled end 14 in order that they may conform to the contour of the ends of the adjacent sections of the polishing block. Each of the blocks 11 and 12 is provided with a central bore 15 being countersunk at 16 to accommodate the head 17 of the bolt 18, a set collar 19 being adapted to be rigidly secured upon

each bolt by means of a set screw 20, said set collar lying against the outer face of the retaining block. Each of the bolts 18 is provided with a screw threaded end 21 which is located through the screw threaded aperture 22 in the end plate 9 of the frame and a jam nut 23 is provided upon each bolt, a squared portion 24 being formed upon the bolt for the purpose of applying a wrench or other tool for turning the same. For the purpose of holding the sections 4 of the polishing block at all times in contact with the surface of the roll a spring 25 is interposed between the rear face of each section and the rear wall 26 of the frame. These springs 25 are for the purpose of compensating for any wear upon the scraping edges of the different sections of the polishing block. A bolt 27 and nut 28 are provided for securing each of the springs 25 to the frame.

85

An angular bracket 29 is provided upon the housing at either end of the roll and adapted to carry the polishing device, the frame 8 resting upon the shelf 30 of each bracket. A shaft 31 is journaled in the end plates 9 of the frame and is provided near each extremity with an elliptical cam 32 rigidly secured upon said shaft by means of a key 33. An operating handle 34 is also rigidly secured at one end of the shaft by means of the key 33 and adapted to engage a suitable rack bar 35. This cam arrangement is for the purpose of moving the entire frame toward the roll so as to bring all of the sections of the polishing block into contact with the roll in unison and this is accomplished by means of the eccentric faces of the cams 32 being brought into contact with the vertical arms 36 of the brackets 29.

It will be understood that this polishing device is adapted to be permanently located upon the mill, it only being necessary to adjust the polishing block with relation to the roll.

This polisher does not interfere with the work of turning out the product of the mill and is continuously polishing the rolls while they are in operation thus obviating the necessity of frequently discontinuing the use of the mill while the rolls are being repolished.

Although the polishing block is generally kept in contact with the surface of the roll it will of course be understood that if at any time it is desired to move the block out of contact with the roll this may be accomplished by operation of the lever and cam device.

Although the drawings and above specification disclose the best mode in which we have contemplated embodying our invention we desire to be not limited to the details of such disclosure, for, in the further practical application of our invention, many changes in form and construction may be made, as

130

circumstances require or experience suggests, without departing from the spirit of the invention, within the scope of the appended claims.

5 We claim:

1. A roll polisher for a rolling mill adapted to polish the surface of a roll during the operation of the mill, said roll polisher comprising in combination with said roll, a polishing block provided with scraping edges and formed of sections rigidly held together within a frame, each of said sections provided with a V-shaped notch in one end, the other end thereof being beveled to conform to the V-shaped notch in the next adjacent section, a spring contacting with each of said sections and adapted to hold the scraping edges of said sections in contact with the surface of said roll and cams adapted to move said frame toward said roll.

2. A roll polisher for a rolling mill adapted to polish the surface of a roll during the operation of the mill, said roll polisher comprising in combination with said roll, a polishing block provided with scraping edges and formed of sections, each of said sections provided with a V-shaped notch at one end, the opposite end of said section being beveled to conform with the V-shaped notch in the next adjacent section, a frame adapted to carry said polishing block, means interposed between said retaining block and the end walls of said frame for holding said sections rigidly together, a spring interposed between the rear face of each section and said frame for moving said sections individually for bringing the scraping edges into contact with the surface of said roll, brackets located on the housing of said mill

and adapted to carry said frame and a cam device acting against said bracket to move said frame toward said roll.

3. A roll polisher for a rolling mill adapted to polish the surface of a roll during the operation of the mill, said roll polisher comprising in combination with said roll, a polishing block provided with scraping edges and formed of sections rigidly held together within a frame, each of said sections provided with a V-shaped notch in one end, the other end thereof being beveled to conform to the V-shaped notch in the next adjacent section, means adapted to move said frame toward said roll, and means for variously distributing the pressure of the said sections against the surface of said roll.

4. A roll polisher for a rolling mill adapted to polish the surface of a roll during the operation of the mill, said roll polisher comprising in combination with said roll, a polishing block formed of sections rigidly held together within a frame, each of said sections provided with a V-shaped notch in one end, the other end thereof being beveled to conform to the V-shaped notch in the next adjacent section, individual means for holding each of said sections in contact with the roll and means for moving said frame toward said roll.

In testimony that we claim the above, we have hereunto subscribed our names in the presence of two witnesses.

JOSEPH DANIELS.
